United States Patent Office

Des. 196,324
Patented Sept. 17, 1963

196,324

BOTTLE OR THE LIKE

Alfred D. Sterges, Los Angeles, Calif., assignor to Purex Corporation, Ltd., Lakewood, Calif., a corporation of California

Filed Nov. 26, 1962, Ser. No. 72,606

Term of patent 14 years

(Cl. D58—5)

FIG. 2.

FIG. 1.

FIG. 3.

FIG. 4.

FIG. 1 is a view showing in side elevation my new design for a bottle;

FIG. 2 is an elevation of FIG. 1 as viewed from the right thereof;

FIG. 3 is an elevation of FIG. 1 as viewed from the left thereof; and

FIG. 4 is a plan view of FIG. 1.

I claim:

The ornamental design for a bottle or the like, substantially as shown.
